OIL CLEANER

Haven Kennison and Rudy I. Peterson,
Minneapolis, Minn.

Application December 17, 1945, Serial No. 635,444

7 Claims. (Cl. 210—57)

1

Our invention relates to an improvement in oil cleaners wherein it is desired to provide a simple and efficient apparatus for removing foreign particles from oil and the like.

In most oil filters with which we are familiar oil is forced through a body of filtering material which acts to strain foreign particles from the oil. Some oil filters are likewise provided with a sediment trap into which foreign particles may settle. Most of these previous devices, however, soon become fouled to such an extent as to render the filters inoperable to serve their intended purpose.

It is an object of the present invention to provide an oil cleaner which separates sludge from oil as the oil travels about a spiral path. Movement of the oil along this path tends to force foreign particles and sludge outwardly against the wall of an outer container permitting these foreign particles and sludge to drain into a sludge receptacle.

A feature of the present invention resides in the provision of a means for guiding oil through a spiral path and to then guide the oil upwardly with a relatively sharp change of direction to separate sludge and foreign particles from the oil.

A further feature of the present invention resides in the provision of an outer casing and an inner member supported within the casing in close proximity to the inner walls of the outer casing. Oil is permitted to travel between the two casings.

A further feature of the present invention resides in the provision of an oil cleaner having an outer casing and an inner baffle. Spiral grooves are provided between the outer casing and the inner baffle so as to guide the oil in a downwardly extending spiral path between the casing and the baffle.

These and other objects and novel features of our invention will be more clearly and fully set forth in the following specification and claims.

In the drawings forming a part of our specification:

Figure 1 is a vertical sectional view through our oil cleaner showing the construction thereof.

Figure 2 is an elevational view of the casing of the filter shown in Figure 1.

Figure 3 is a top plan view of the casing shown in Figure 2.

Figure 4 is a side elevational view of the cleaner element which is positioned within the outer casing.

Figure 5 is a modified form of construction in which additional oil baffles are provided.

2

The oil cleaner A illustrated in Figures 1 through 4 of the drawings comprises a casing 10 having an upper ball shaped portion 11 and a lower ball shaped portion 12 which are connected by a connecting neck 13. The casing 10 may be formed of any suitable material and may be formed in several parts connected together or may be formed in two parts as illustrated.

The upper ball shaped portion 11 of the casing 10 includes upper and lower semi-spherical sections 14 and 15 respectively. The sections 14 and 15 are provided with marginal flanges 16 and 17 respectively which are bolted together by bolts or other means 19. A gasket 20 is preferably provided between the two sections 14 and 15 to seal the joint therebetween.

A boss 21 extends vertically from the top of the section 14 and an aligned boss 22 extends inwardly from the hollow semi-spherical shell 14. The aligned bosses 21 and 22 form a nipple extending partially into the upper section 14 and extending partially externally thereof. The bosses 21 and 22 are provided with an axial opening 23 therethrough which is internally threaded. A nipple 24 is partially threaded into the boss 22 and projects inwardly therefrom.

Within the upper portion 11 of the body 10 we provide a baffle 25. This baffle 25 is provided with a flat or slightly tapered upper surface 26 and a spherical wall 27 having an outer diameter to fit within the inner wall of the upper portion 11 of the body 10. The flat upper baffle surface 26 is provided with a downwardly extending boss or sleeve 29 thereupon which is internally threaded to receive the projecting end of the nipple 24.

In other words, the baffle 25 fits within the upper section 11 of the casing and is supported by the nipple 24 mounted in the boss 22. As a result the nipple 24 may provide not only a support for the baffle 25, but also a means of egress of the oil from the interior of the baffle 25.

The baffle 25 is provided with an outer grooved surface as best illustrated in Figure 4 of the drawings. The spiral grooves 30 extend around the exterior of the spherical wall 27 of the baffle and act to guide oil along a spiral path between the baffle 25 and the inner wall of the upper portion 11 of the casing. An aperture 31 is provided at the lower extremity of the baffle 25 through which oil may enter the interior of the hollow baffle. The baffle 25 is shown as having projecting ribs 32 between the grooves 30. In actual practice these ribs 32 may be formed by some other means such as by winding wire or rod spirally about the outer wall of the baffle 27 in a manner

to produce spiral grooves between adjacent convolutions. The intent of the structure is to guide the oil along a downwardly extending spiral path as it passes between the baffle 25 and the casing.

It will be noted that the baffle 25 is slightly spaced from the inner wall of the casing 10. The space provided between the baffle and the casing is ordinarily not sufficient to permit the flow of oil to merely travel down the inner walls of the casing without being affected by the spiral grooves. The space between the baffle and the casing, however, permits the sludge in the oil to be deposited upon the inner casing wall in position to drain downwardly as the oil follows its spiral path. Obviously a certain amount of oil will be permitted to flow downwardly along the casing wall. This oil helps to flush the sediment and impurities of the oil downwardly into the lower portion 12 of the casing 10.

The neck 13 of the casing is provided with an axial passage 33 therethrough through which sediment and impurities may drop into the lower casing portion 12. An internally threaded sleeve 34 is provided at the lower extremity of the casing portion 12 for accommodation of a plug 35. By removing the plug 35 the collected sediment in the casing portion 12 may be drained and removed.

In operation the oil cleaner is placed in the oil line to receive oil usually under some pressure. A boss 38 extends tangentially from the upper portion 11 of the casing 10 near the upper extremity thereof. A passage extends through this boss 38 and communicates with the interior of the upper casing portion above the level of the baffle 25. Thus the oil entering the upper portion of the cleaner is urged in a circular direction about the top of the baffle, creating a circular movement of the oil which tends to guide the oil into the grooves 30.

The oil is thus guided into the spiral grooves 30 where it travels downwardly in a spiral path. The movement of the oil in this spiral path tends to throw the impurities and sludge carried by the oil against the inner surface of the casing wall. This sludge is free to drain slowly downwardly along the inner casing wall into the lower ball shaped portion 12 of the casing. This downward movement of the sludge and impurities is aided by the portion of oil which flows downwardly exteriorly of the ribs 32.

The oil after passing the baffle 25 fills the sludge receptacle 12 and then passes through the aperture 31 filling or partially filling the interior of the baffle 25. The oil then passes through the nipple 24 and the passage 23 to continue along the oil line. Once the oil cleaner has been filled with oil, movement of oil through the cleaner begins immediately upon introduction of more oil through the inlet 35.

We have illustrated the baffle 25 as having a spherical bottom portion extending from the flat top 26 to the lower extremity of the baffle. It is not entirely essential that the baffle be as long as is illustrated to accomplish its result. In Figure 5 of the drawings we disclose a baffle which is considerably shorter than the baffle 25 and which may be used in place thereof.

The oil cleaner B, illustrated in Figure 5 of the drawings, includes an upper shell shaped section 36 and a lower shell shaped section 37 connected by a connecting neck 39. An integral sleeve 40 is provided at the bottom of the lower section 37. This sleeve 40 is internally threaded

at 41 to accommodate the drainage plug not illustrated in the drawings.

The section 36 is preferably formed of two semi-spherical shells 42 and 43 which are provided with integral flanges 44 and 45, respectively, connected by some means such as by the bolts 46. An internally threaded sleeve 47 is provided at the top of the uppermost shell 42 which sleeve extends partially into the casing and extends partially out of the casing. The inwardly extending sleeve portion accommodates an externally threaded nipple 49 which acts as a support for the baffle 50.

The baffle 50 is provided with a flat or slightly tapered top 51 and a double wall 52 having an arcuated outer surface. Ribs 53 which are in spaced relation and are spiral in shape are provided on the outer surface of the wall 52 producing grooves 54 between the ribs through

which oil may flow.

The baffle 50 is provided with a central boss 55 which is internally threaded to accommodate the nipple 49. The baffle 50 is preferably provided with its outer surface in slightly spaced relation to the interior walls of the casing section 36.

As an added baffle to assist in removing sludge and impurities, we provide a cylindrical sleeve 56 concentric with the central boss 55 and depending from the top portion 51 of the baffle 50. This sleeve 56 extends into overlapping relation with a concentric cylindrical sleeve 57 which extends upwardly from the lower shell 43 adjacent the passage 59 through the neck 39. Passages 60 are provided between the lower extremities of the sleeve 57 and the shell 43 to permit the sludge and impurities to drain into the sludge trap portion 37.

The operation of this type of cleaner is similar to that previously described, oil enters the inlet 61 and tends to travel in a circular direction. The oil is guided outwardly by the baffle 50, passing through the spiral passages 54 between the grooves 53. This spiral movement of the oil tends to throw impurities and sludge outwardly against the inner casing wall where it is free to drain downwardly into the sludge trap portion 37.

The oil flows into the lower shell 43 outwardly of the cylindrical sleeve 57 and is deflected upwardly over the top of this sleeve. This quick change in direction of the oil assists in removing impurities therefrom. The apertures 60 are of insufficient size to accommodate the flow of oil and thus prevent a by-pass of the oil directly into the inner baffle sleeve 56.

After passing over the upper extremity of the sleeve 57 the oil travels downwardly again before its direction is changed to pass through the oil 62. Thus with the cleaner B there are additional quick changes of direction in the flow of oil which tend to assist in removing foreign particles therefrom.

In accordance with the Patent Statutes, we have described the principles of construction and operation of our oil cleaner and while we have endeavored to set forth the best embodiments thereof, we desire to have it understood that obvious changes may be made within the scope of the following claims without departing from the spirit of our invention.

We claim:

1. An oil cleaner comprising an outer casing, a baffle in said casing in closely spaced relation to the walls thereof, an oil inlet at the top of said

casing and an outlet within said baffle, said baffle guiding the oil between said baffle and said casing, and downwardly inclined grooves, the grooves being substantially deeper than the distance between the baffle and the casing in the outer surface of said baffle.

2. An oil cleaner comprising a ball shaped casing, a baffle within said casing, said baffle being shaped to fit the contour of the inner surface of said casing and spaced slightly therefrom, an oil inlet above said baffle, downwardly inclined grooves in the periphery of said baffle, said grooves guiding oil about the periphery of said baffle as it flows downwardly, a sediment receptacle below said baffle and an outlet from said casing.

3. An oil cleaner comprising a casing, a baffle within said casing, a series of downwardly inclined grooves in said baffle through which oil may flow, an oil outlet at the top of said casing, a boss projecting downwardly in said casing through which the outlet extends a nipple in said boss, said nipple extending into said baffle for supporting the same, said baffle being engageable against said boss to properly locate the baffle, an oil inlet above said baffle and a passage through said baffle communicating with said nipple to provide an oil outlet.

4. An oil cleaner comprising an outer casing, a baffle within said casing, said baffle having a series of peripheral grooves thereabout for guiding oil about the periphery of the baffle as it travels between said baffle and said casing, an oil inlet above said baffle, an upstanding baffle extending within said first named baffle, and an auxiliary baffle on said first named baffle extending downwardly from said first named baffle into overlapping relation with said second baffle, a sediment receptacle below said baffle and an outlet communicating with the interior of said auxiliary baffle.

5. An oil cleaner comprising an outer casing, a baffle within said casing, an oil inlet above said baffle, passage means between said baffle and said casing, said passage means guiding oil passing the baffle about the periphery of the baffle, and a pair of substantially cylindrical ring-shaped baffles arranged one within the other, the outer of said ring-shaped baffles extending upwardly within said casing and the other of said ring shaped baffles extending downwardly from said first named baffle into said outer ring shaped baffle, a sediment receptacle below said baffle and an oil outlet in the top of the casing communi-

cating with the interior of said other ring shaped baffle.

6. An oil cleaner comprising an outer casing, a baffle within said casing, an oil inlet above said baffle, passage means between said baffle and said casing, said passage means guiding oil passing the baffle about the periphery of the baffle, and a pair of substantially cylindrical ring-shaped baffles arranged one within the other, the outer of said ring-shaped baffles extending upwardly within said casing and the other of said ring shaped baffles extending downwardly from said first named baffle into said outer ring shaped baffle, and an oil outlet in the top of the casing communicating with the interior of said other ring shaped baffle, said first ring-shaped baffle having apertures therethrough at the juncture of said baffle and said casing to permit sludge to drain therethrough.

7. An oil cleaner comprising a ball shaped compartment, a baffle within said compartment having an outer shape to fit a contour of the inner walls of said casing and spaced slightly therefrom, spiral groove means between said baffle and said casing, an oil inlet above said baffle, a sludge chamber beneath said ball shaped casing and communicating therewith, and an oil outlet at the top of said ball shaped casing, said outlet extending through said baffle.
